UNITED STATES PATENT OFFICE.

JAMES B. JOHNSTON, OF PHILADELPHIA, PENNSYLVANIA.

ICE-MAKING MACHINE.

No. 861,780.

Specification of Letters Patent.

Patented July 30, 1907.

Application filed July 16, 1906. Serial No. 329,318.

To all whom it may concern:

Be it known that I, JAMES B. JOHNSTON, a citizen of the United States, residing at the city of Philadelphia, in the county of Philadelphia and State of Pennsylvania, have invented certain new and useful Improvements in Ice-Making Machines, of which the following is a specification.

My invention has relation to an ice making machine for principally household purposes, and of that 10 class adapted to congeal liquids under the influence of a refrigerative treatment induced in the machine by the creation and maintenance of a vacuum therein; and in such connection it relates more particularly to the constructive arrangement of the machine 15 for effectually carrying out the defined purposes of the invention.

The principal objects of my invention are first, to provide a machine of the character described, with means to permit of the formation of clear or crystalline 20 ice in block or cake form and without the presence of air needles therein in contradistinction to snow ice, such as heretofore produced by vacuum resort to methods; and second, to so arrange the machine as to concentrate the refrigerative treatment 25 to a vessel adapted to contain the liquid to be quickly formed into a block of ice.

The nature and scope of my present invention will be more fully understood from the following description taken in connection with the accompanying 30 drawings forming part hereof, in which

Figure 1, is a view, illustrating in elevation an ice-making machine, a vacuum pumping means for exhausting the air therefrom, and of means for manually actuating the same, embodying main features 35 of my said invention, and Figs. 2 and 3, are respectively views, illustrating in vertical central section and in horizontal section, the upper portions of the machine.

Referring to the drawings 4, represents a receptacle 40 of preferably annular outline, in cross-section, which is supported by a frame-work, consisting of a ring 5, and standard 6, connected with the receptacle by braces 7. At the upper or open end, the receptacle 4, is provided with a flange 8, adapted to support a 45 washer or gasket 9, and a series of clamping bolts 10, which by engaging the flange 13, of a lid 12, through the intervention of thumb-nuts 11, in conjunction with the washer 9, hold the lid air tight as well as readily removable, on the receptacle or vessel 4. 50 The lid 12, is provided with a centrally arranged opening 14, of a predetermined diameter, and with a flange 15, on which is mounted a washer or gasket 16, engaged by the flange 13, of a cap or cover 17. The cap 17, is provided with an extension 18, engaging 55 the inner surface of the flange 15, and is forced

against the washer 16, by a threaded bolt 20, arranged in a bail 21, pivotally secured in the points 22, to the lid 12, as shown in Fig. 2. By this arrangement the cap 17, is likewise held air tight upon the lid 12, and may be readily disengaged therefrom, by loosening 60 the bolt 20. Within the receptacle 4, are arranged receptacles 23, 24, 25 and 26, of decreasing size, nested within each other and respectively open at their upper ends. These receptacles are held apart and in proper position with respect to each other by vertical struts 27, and horizontal distance pieces 28. By the nested receptacles 23, 24, 25 and 26, the interior of the receptacle 4, is divided into chambers 29, 30, 31 and 32, of which the chamber 29, forming the outermost of said chambers, is adapted to receive 70 a non-conducting substance or material of heat or cold, such as charcoal, the chamber 30, a hygroscopic material, such as salt or analogous matter, the chamber 31, a freezing medium, such as ice in lump form, while the chamber 32, remaining empty 75 for a purpose to be presently explained. The innermost receptacle 26, of the said receptacles surrounded respectively by layers of charcoal, salt, ice and air, is adapted to receive the liquid to be congealed or frozen, for instance, said receptacle is filled with 80 water to near the openings 34, which are adapted to permit of the insertion of an implement by means of which, this receptacle 26, can be readily removed, from the receptacle 4, after the cap 17, has been disengaged from the lid 12, thereof.

The chamber 29, containing charcoal or other insulating material is closed at the upper end by a cap 35, and the chamber 31, containing ice is closed by a perforated cap or wire gauze 36. Thus the chambers 30, 31 and 32, as well as the receptacle 26, containing the 90 water, are at their upper ends at all times, in open communication with a chamber 37, formed by the lid 12, and cap 17. Within the chamber 37, terminates the tubular portion 39, of a spigot 38, to which is secured preferably a metal tubing 40, connected with a vacuum 95 pump 41, of any suitable well known construction. The piston-rods 42, of the pump, are formed into racks which are engaged by a gear-wheel 43, and oscillated by a link 44, crank-arm 45, and a hand-lever 46, pivoted in the point 47, to the receptacle 4. When the pump 100 41, is manually actuated by means of the lever 46, the air is exhausted from the chambers 37, 32 and 31, and a vacuum is created and maintained in the receptacle 4. The vacuum produced in the receptacle 4, and the absorption of the vapor by the salt, in the chamber 30, 105 causes a rapid evaporation of the liquid in the receptacle 26, so as to speedily lower the temperature of the same, to about or below the freezing point. The ice placed in the chamber 31, assists in speedily lowering the temperature, and the air by being exhausted from 110

the ice chamber 31, passes through openings 33, in the receptacle 25, in the form of diminutive streams and directed against the bottom and surfaces of the receptacle 26, to thereby reduce the temperature of such wall which acts on the liquid of the receptacle to rapidly freeze or congeal the same therein into a clear crystal-like block of ice. This is still further advanced by the contents of the chamber 31, permitting the freezing temperature thereof to act upon the bottom and all surfaces of the receptacle 26. The water thus rapidly frozen in the receptacle 26, will form therein a block or cake of crystal-like ice free from air needles or bubbles slowly melting when exposed to the influence of a normal temperature. In order to permit of ready disengagement of the cap 17, from the lid 12, to remove the ice by lifting the receptacle 26, out of the freezing receptacle 4, the same is provided with an additional air cock 48, which by being actuated instantly relieves the vacuum. The insulating layer of charcoal or other material in the chamber 29, being a non-conductor of heat, assists in the rapidly lowering of the temperature of the freezing receptacle 4, and thus the freezing or congealing of the water in the receptacle 26, is accom-

plished in a much less time than was hitherto possible in vacuum machines for snow ice making.

Having thus described the nature and objects of my invention, what I claim as new and desire to secure by Letters Patent is:—

In an ice making machine, a receptacle having a lid and forming a vacuum chamber, vessels arranged in said receptacle, supporting means respectively interposed between said receptacle and vessels to form chambers therebetween, said chambers adapted to respectively contain an insulating material, a hygroscopic material and matter to assist in the lowering of the temperature, a vessel adapted to contain liquid to be frozen arranged within the innermost of said vessels and adapted to form in conjunction therewith a chamber in communication with the vacuum chamber formed by said receptacle, vessels and lid of said receptacle, and the innermost of said vessels having openings adapted to permit of free action of said matter upon the vessel containing the liquid.

In testimony whereof, I have hereunto set my signature in the presence of two subscribing witnesses,

JAMES B. JOHNSTON.
